(57) **CLAIM**

The ornamental design for a display screen with icon group and display screen with icon set, as shown and described.

DESCRIPTION

FIG. 1 is a front view of a display screen with icon group showing our new design; and,

FIG. 2 is a front view of a display screen with icon set showing our new design.

The broken line showing of portions of the display screen forms no part of the claimed design. The bracket in FIG. 2 indicates an icon set and forms no part of the claimed design.

1 Claim, 2 Drawing Sheets
